UNITED STATES PATENT OFFICE.

CHARLES M. YOUNG, JR., OF PHILADELPHIA, PENNSYLVANIA, ASSIGNOR TO LINK-BELT COMPANY, OF CHICAGO, ILLINOIS, A CORPORATION OF ILLINOIS.

SKIP HOIST.

Application filed September 8, 1925. Serial No. 54,854.

To all whom it may concern:

Be it known that I, CHARLES M. YOUNG, Jr., a citizen of the United States, residing at Philadelphia, in the county of Philadelphia and State of Pennsylvania, have invented a certain new and useful Improvement in Skip Hoists, of which the following is a specification.

This invention relates to a skip hoist and to automatic means for filling the same from a bin or other receptacle containing material, and adapted upon operation of the hoist to discharge the same into the bucket or skip. It has for one object to provide a device by means of which the material may be readily discharged into the bucket without spilling. Another object is to provide a device of the type mentioned with a light, durable and readily operated gate for controlling the flow of material from the bin or other receptacle in response to the movement of the bucket into which it is to be discharged. Other objects will appear from time to time throughout the specification and claims.

My invention is illustrated more or less diagrammatically in the accompanying drawings, wherein:

Figure 1 is a side elevation with parts in section of the skip bucket in the receiving position, showing the gate and chute mechanism;

Figure 2 is a similar view, with parts omitted showing the gate closed;

Figure 3 is a section on the line 3—3 of Figure 1;

Fig. 4 is a fragmentary view showing the contact member on the chute moved to inoperative position.

Like parts are indicated by like characters throughout.

A is a track. A¹ is a skip bucket supported from the track by means of the wheels A² and adapted to move therewith.

B is a bail supporting the bucket as at B¹ and having joined to it a cable B².

C C are contact rollers supported on arms C¹ C¹. D is a hopper or receptacle in which the material to be deposited in the bucket is first placed. D¹ is a chute leading from it. It is controlled by an undercut gate formed of a gate portion E and a pair of side members E¹ each having an arcuate portion E² and rearwardly extending arms E³. These arms are pivoted on a

shaft E⁴ which is supported in the bearings E⁵ on the chute D¹. The arms E³ are joined by a connecting member E⁶ upon which are placed the movable counterweights E⁷ which are held against accidental displacement by bolts E⁸. E⁹ is an outwardly turned lip on the undercut gate E. It is adapted to contact the bottom part of the guide member, which is described below.

Pivoted also on the shaft E⁴ is a guide member F. It is formed with bottom and side members, the latter being joined at the discharge end by a baffle member F¹. Additional baffle members F² F² are placed in suitable locations throughout the length of the guide member F. They may be provided with reinforcing angle members F³ F³. F⁴ is a closed bottom of the guide member. As shown it extends only throughout a part of the length of the guide member, terminating adjacent the undercut gate.

G G are perforated bracket members on the sides of the guide member F. In each of them is positioned a bolt G¹. G² is an outwardly projecting ring on each of the members E¹. The bolt is slidably positioned through this ring. G³ G³ are adjustably mounted locking nuts on the bolt G¹. Between the ring G² and the nuts G³ on each of the bolts G¹ is a helical spring G⁴. By means of this construction limited cushioned relative movement of the undercut gate and the guide member is permitted.

H H are contact plates, one located on each side of the guide member F and adapted to be contacted by the rollers C, as shown in the drawings, or to be moved out of position.

I is a baffle member adjustably mounted in the chute D¹. As shown it is held in position by bolts I¹ and I², the latter extending through an arcuate slot I³. By means of this construction the member I may be rotated throughout a limited arc in order to adjust its position within the discharge mouth of the chute D¹.

The adjustable baffle member or flow plate I by means of its adjustability permits adjustment of the size of the opening through which the material passes so as to control the point where the material strikes the first baffle plate on the open guide member F, thereby permitting adjustment for the use of material having a flat angle of repose as well as material having a steep angle of repose.

This adjustability of the flow plate also permits control of the point where the angle of repose of the material intersects the outer edge of the bottom plate of the guide member or chute as the same is rotated upward, thus causing material to stop flowing from the guide member or chute earlier than would be the case in an uncontrolled discharge passage. And for a given adjustment the amount of material remaining in the upturned guide member when the same is in the closed position shown in Figure 2, it is reduced, and thus reduces the chance of spilling material.

15 The contact plates may be rotated into the position shown in Figure 4 and in that position the rollers C of the bucket A¹ will not contact the plates and thus the bucket may be raised and lowered past the contact plates

20 without opening the gate assembly. Although I have shown an operative device, still it will be obvious that many changes might be made in size, shape and arrangement of parts without departing materially from the spirit of my invention; and I wish therefore, that my showing be taken as in a sense diagrammatic.

The use and operation of my invention are as follows:

30 When it is desired to use the skip, material is deposited in the main bin and the necessary hoisting machinery is set in operation, to lower the skip bucket until the the contact rollers on it strike the contact plates on the side of the guide member. Sometimes this contact is very violent, and it is to cushion the violence of the shock due to this contact that the gate and guide member are mounted for relative cushioned movement. Thus the

40 guide member may start downward toward the opening position slightly ahead of the undercut gate. As soon as the shock of the contact has been absorbed, the two will move substantially together.

45 As movement continues, the guide member turns into the bucket and the undercut gate moves out of its closing position in the bottom of the chute and permits discharge of the material through it into the skip bucket.

50 The baffle plates located along the open top of the guide member prevent spilling or discharge of material, because as material rushes through the chute and the guide member, it contacts these baffles and is prevented from overflowing through the top of the guide member. In case the material

55 comes to a standstill with the parts in the open or loading position, it will find its angle of repose against successive baffles and no discharge through the bucket and guide member will take place.

60 When the bucket is full, the hoisting mechanism operates to reverse its movement and the bucket is raised. As it does so the counterweights swing the undercut gate and the

guide member upward, and thus the guide member moves out of the open mouth of the bucket and the undercut gate closes the discharge opening from the chute and the parts thus assume the position shown in Figure 2, 70 in which position no discharge can take place.

I claim:

1. In combination with a chute, a chute closing member adapted to move to prevent discharge therethrough, said member formed with a pair of side members and provided with a generally arcuate chute closing gate portion, and an open guide member adapted to move with said gate, and to have limited 75 cushioning movement relative thereto.

2. In combination with a chute, a chute closing member adapted to move to prevent discharge therethrough, said member formed with a pair of side members pivoted on a portion of said chute, and provided with a generally arcuate chute closing gate portion, and an open guide member pivoted also on said chute adapted to move with said gate and to have limited cushioning 80 movement relative thereto.

3. In combination with a chute, a chute closing member adapted to move to prevent discharge therethrough, said member formed with a pair of side members pivoted on a portion of said chute, and provided with a generally arcuate chute closing gate portion, extensions therefrom, and counterweights supported from said extensions, and an open guide member pivoted also on said chute adapted to move with said gate and to have limited cushioning movement relative thereto.

4. In combination with a chute, a chute closing member adapted to move to prevent discharge therethrough, said member formed of a pair of side members pivoted on a portion of said chute, and provided with an arcuate chute closing gate portion, extensions therefrom and removable counterweights supported from said extensions, and an open guide member pivoted also on said chute adapted to move with said gate and to have limited cushioning movement relative thereto, said guide member provided with a contacting portion in combination with a bucket having a contacting member adapted to contact said contacting portion to open the chute closing member and to move the guide member into operative position.

5. In a skip hoist, a chute, and a skip adapted to be filled therefrom, in combination with a chute closing member adapted to be moved in response to the movement of the skip to prevent discharge therethrough, said member formed of a pair of side members provided with an arcuate chute closing gate portion, and an open guide member adapted to move with said gate and to have 130

- limited cushioning movement relative thereto.
6. In a skip hoist, a chute, and a skip adapted to be filled therefrom, in combination with a chute closing member adapted to be moved in response to the movement of the skip to prevent discharge therethrough, said member formed of a pair of side members pivoted on a portion of said chute, provided with an arcuate chute closing gate portion, and an open guide member pivoted also on said chute adapted to move with said gate and to have limited cushioning movement relative thereto.
- 15 7. In a skip hoist, a chute, and a skip adapted to be filled therefrom, in combination with a chute closing member adapted to be moved in response to the movement of the skip to prevent discharge therethrough, said member formed of a pair of side members pivoted on a portion of said chute, and provided with an arcuate chute closing gate portion, extensions therefrom, and removable counterweights supported from said extensions, and an open guide member pivoted also on said chute, adapted to move with said gate and to have limited cushioning movement relative thereto.
- 30 8. In a skip hoist, a chute, and a skip adapted to be filled therefrom, in combination with a chute closing member adapted to be moved in response to the movement of the skip to prevent discharge therethrough, said member formed of a pair of side members pivoted on a portion of said chute, and provided with an arcuate chute closing gate portion, extensions therefrom and removable counterweights supported from said extensions, and an open guide member pivoted also on said chute adapted to move with said gate and to have limited cushioning movement relative thereto, said guide member provided with a contacting portion in combination with a bucket having a contacting member adapted to contact said contacting portion to open the chute closing member and to move the guide member into operative position.
- 45 9. In combination with a chute, a chute closing member adapted to move to prevent discharge therethrough, said member formed with a pair of side members and provided with a generally arcuate chute closing gate portion, and an open guide member adapted to move with said gate, and an adjustable throat member for said chute whereby the size of the discharge opening may be varied.
- 60 10. In combination with a chute, a chute closing member adapted to move to prevent discharge therethrough, said member formed with a pair of side members pivoted on a portion of said chute, and provided with a generally arcuate chute closing gate portion, and an open guide member pivoted also on said chute adapted to move with said gate and to have limited cushioning movement relative thereto.
11. In a skip hoist, a chute, and a skip adapted to be filled therefrom, in combination with a chute closing member adapted to be moved in response to the movement of the skip to prevent discharge therethrough, said member formed of a pair of side members provided with an arcuate chute closing gate portion, and an open guide member adapted to move with said gate, a contact member on said chute closing member adapted to be contacted by a part of said skip, said member adapted to be moved out of the path of said skip, whereby the skip may be moved past it without contacting it.
- 15 12. In a skip hoist, a chute, and a skip adapted to be filled therefrom, in combination with a chute closing member adapted to be moved in response to the movement of the skip to prevent discharge therethrough, said member formed of a pair of side members pivoted on a portion of said chute, provided with an arcuate chute closing gate portion, and an open guide member pivoted also on said chute adapted to move with said gate and to have limited cushioning movement relative thereto, a contact member on said chute closing member adapted to be contacted by a part of said skip, said member adapted to be moved out of the path of said skip whereby the skip may be moved past it without contacting it.
- 25 13. In combination with a chute, a chute closing member, adapted to be moved to prevent discharge therethrough, in combination with an open guide member adapted to move with said closing member and to guide the discharge of material from the chute, said closing member and guide member being mounted for relative movement and provided with yielding means for resisting such movement.
- 40 14. In combination with a chute, an undercut gate, adapted to be moved to prevent discharge through said chute, an open guide member mounted to move with said gate and adapted to guide the discharge of material from the chute, said closing member and guide member being mounted for relative movement and provided with yielding means for resisting such movement.
- 45 15. In combination with a chute, a chute closing member, adapted to be moved to prevent discharge therethrough, in combination with an open guide member adapted to move with said closing member and to guide the discharge of material from the chute, and a baffle within and extending across said guide member, said closing member and guide member being mounted for relative movement and provided with yielding means for resisting such movement.
- 60 16. In a skip hoist, a chute, and a skip adapted to be filled therefrom, a chute clos-

- ing member adapted to be moved to prevent discharge through said chute, in combination with an open guide member mounted to move with said closing member, and adapted 5 to guide the discharge of material from the chute, said closing member and guide member being mounted for relative movement and provided with yielding means for resisting such movement.
- 10 17. In a skip hoist, a chute, and a skip adapted to be filled therefrom, a chute closing member adapted to be moved to prevent discharge through said chute, in combination with an open guide member mounted to 15 move with said closing member, and adapted to guide the discharge of material from the chute, and to bridge the gap between the end of said chute and said skip, said closing member and guide member being mounted 20 for relative movement and provided with yielding means for resisting such movement.
18. In a skip hoist, a chute, and a skip adapted to be filled therefrom, a chute closing member adapted to be moved to prevent discharge through said chute, in combination with an open guide member mounted to move with said closing member, and adapted 25 to guide the discharge of material from the chute, and to bridge the gap between the end of the chute and said skip, said chute closing member adapted to be opened by the downward movement of said skip and provided with a counterweight whereby it is closed automatically as the skip moves upward, 30 said closing member and guide member being mounted for relative movement and provided with yielding means for resisting such movement.
- 35 19. In a skip hoist, in combination a chute and a skip adapted to be filled therefrom, an undercut gate adapted to be moved to prevent discharge through said chute, an open guide member mounted to move with said gate and adapted to guide the discharge of material from the chute, said closing member and guide member being mounted for relative movement and provided with yielding means for resisting such movement.
- 40 20. In a skip hoist, in combination a chute and a skip adapted to be filled therefrom, an undercut gate adapted to be moved to prevent discharge through said chute, an open guide member mounted to move with said gate and adapted to guide the discharge of material from the chute, and to bridge the gap between the discharge end of the said chute and said skip said undercut gate and said guide member mounted for limited relative movement and yielding means for resisting such movement.
- 45 21. In a skip hoist, in combination a chute and a skip adapted to be filled therefrom, an undercut gate adapted to be moved to prevent discharge through said chute, an open guide member mounted to move with said 50 gate and adapted to guide the discharge of material from the chute, and to bridge the gap between the discharge end of said chute and said skip, said guide member having within and extending across it a plurality of baffles, said undercut gate and said guide member mounted for limited relative movement and yielding means
- gate and adapted to guide the discharge of material from the chute, and to bridge the gap between the discharge end of said chute and said skip, said guide member having within and extending across it a plurality of baffles, said undercut gate and said guide member mounted for limited relative movement and yielding means for resisting such movement.
- 55 22. In a skip hoist, a chute, and a skip adapted to be filled therefrom, a chute closing member adapted to be moved to prevent discharge through said chute, in combination with an open guide member mounted to move with said closing member, and adapted to guide the discharge of material from the chute, said guide member provided with projections, and said skip provided with engaging projections whereby the chute closing member is opened as the skip moves downward and is freed for closing as the skip moves upward, said undercut gate and said guide member mounted for limited relative movement and yielding means for resisting such movement.
- 60 23. In combination with a chute, a chute closing member, adapted to be moved to prevent discharge therethrough, in combination with an open guide member adapted to move with said closing member and to guide the discharge of material from the chute, said closing member and guide member being mounted for relative movement and provided with yielding means for resisting such movement, and an adjustable throat plate mounted in said chute, and adapted to be moved to control the size of said opening.
- 65 24. In combination with a chute, a chute closing member, adapted to be moved to prevent discharge therethrough, in combination with an open guide member adapted to move with said closing member and to guide the discharge of material from the chute, and a baffle within and extending across said guide member, said closing member and guide member being mounted for relative movement and provided with yielding means for resisting such movement, and an adjustable throat plate mounted in said chute, and adapted to be moved to control the size of said opening.
- 70 25. In a skip hoist, in combination a chute and a skip adapted to be filled therefrom, an undercut gate adapted to be moved to prevent discharge through said chute, an open guide member mounted to move with said gate and adapted to guide the discharge of material from the chute, and to bridge the gap between the discharge end of said chute and said skip, said guide member having within and extending across it a plurality of baffles, said undercut gate and said guide member mounted for limited relative movement and yielding means

for resisting such movement, and an adjustable throat plate mounted in said chute and adapted to be moved to control the size of said opening.

- 5 26. In combination with a chute, a chute closing member adapted to be moved to prevent discharge therethrough, in combination with an open guide member adapted to move with said closing member and to
- 10 guide the discharge of material from the chute, said closing member and guide member being mounted for relative movement.
- 27. In combination with a chute, a chute closing member adapted to be moved to

prevent discharge therethrough, in combination with an open guide member adapted to move with said closing member and to guide the discharge of material from the chute, said closing member and guide member being mounted for relative movement, 20 said open guide member being provided with a plurality of baffle plates generally adjacent its open upper side.

Signed at Philadelphia, county of Philadelphia and State of Pennsylvania, this 25 first day of September, 1925.

CHAS. M. YOUNG, JR.
